UNITED STATES PATENT OFFICE.

JAMES TEEVAN AND JAMES F. HOYNE, OF DUBLIN, IRELAND.

LETTER-BOX.

SPECIFICATION forming part of Letters Patent No. 626,251, dated June 6, 1899.

Application filed September 2, 1897. Serial No. 650,341. (No model.)

To all whom it may concern:

Be it known that we, JAMES TEEVAN and JAMES FREDERICK HOYNE, subjects of the Queen of Great Britain and Ireland, residing 5 in Dublin, Ireland, have invented certain Improvements in Letter-Boxes, (for which we have obtained a patent in Great Britain, No. 18,158, bearing date August 21, 1897;) and we do hereby declare that the following is a full, 10 clear, and exact description of the invention, which will enable others skilled in the art to which it appertains to make and use the same.

This invention has reference to improvements in letter-boxes, and is designed for the 15 purpose of preventing the surreptitious removal or extraction of the contents of same; also, to prevent the contents being injured by the introduction of lighted matches, burning 20 cigars or cigarettes, and such like.

The accompanying explanatory drawings will enable our said invention to be more readily understood.

Figure 1 represents a perspective view of a letter-box, one wall partly broken away, showing our invention. Fig. 2 represents a plan view of toothed flap detached. Fig. 3 is a 25 plan of bottom of chute detached.

A is a chute, composed of wood, metal, or other suitable material, which is attached to 30 the inside of the front plate B of the letter-box, so that its upper open end coincides with the ordinary letter-slot. At the free end of this chute is hinged a rectangular flap C, so balanced that a gentle pressure from above 35 (such as a letter descending) will cause it to open. The flap C is maintained in a normally horizontal position by means of the sheet-weight G, secured to the end of the pivot-rod H outside the chute. The flap and weight 40 are, of course, in rigid attachment to said rod. Once a letter or paper or such like falls through this chute the flap permits same to pass into the box and immediately returns to its normal position, while should any attempt 45 be made to surreptitiously extract the contents of the box the presence of the flap will effectually prevent the accomplishment of such design. The free longitudinal edge of the flap may be serrated or pointed to increase 50 its efficiency for the purpose in view.

The bottom side D of the chute is provided with a number of slots, as shown in Fig. 3, of

sufficient width to allow matches, burning cigars, cigarettes, and such like to pass through, but not too wide to interfere with the free passage of letters, periodicals, and such like over its surface. Thus should a lighted match or burning cigar or cigarette be thrown into the letter-slot it passes harmlessly through these slots and is received in a receptacle E, fixed 60 underneath the chute, whereby injury to the contents of the box is prevented.

From the above description it will be obvious that according to our invention the two objects in view are effected—namely, first, 65 the prevention of the surreptitious removal of the contents of letter-boxes, and, second, the prevention of injury to the contents by lighted matches, burning cigars, and such like. In order the more effectually to fulfil 70 the first of these objects, we hinge on the lower edge of the chute a second rectangular flap F, provided with a row of teeth F', projecting parallel to the bottom of the chute, and a row of depending teeth F² almost at 75 right angles to the first. This flap lies in its normal position, as shown in Fig. 1, and in this position it offers no impediment to the descent of letters. Should, however, a rod be introduced for the purpose of rendering 80 the top flap C inoperative while a string is being dropped into the box loaded with adhesive matter, any attempt to draw up the contents in this way will instantly and automatically be resisted by the action of the 85 said flap F. The said flap F is controlled in the same manner as flap C by means of the sheet-weight G', secured to the pivot-rod H', the combined weight of F, F', and F² serving to 90 slightly overbalance said weight.

Having now particularly described and ascertained the nature of our said invention and in what manner the same is to be performed, we would have it understood that what we claim is—

1. The combination in a letter or street mail-box, a chute having a slotted bottom, a hinged flap C, a receptacle located in the upper part of the box immediately below the slotted bottom, and a second flap F beyond 100 the flap C and pivoted at the end of the chute A, to normally occupy a position to form an extension of the slotted bottom, substantially as herein specified.

2. The combination with a street letter or mail - box, of the chute A, having slotted bottom D, receptacle E, below said bottom, flap C maintained in vertical position by gravity but partly counterbalanced by weight G, and a second flap F having in line therewith teeth F' and a second series of teeth F² at right angles therewith, and weight G' partially balancing said last-mentioned flap, all substantially as herein specified.
3. In a letter or street mail-box, the combination of a chute, an intercepting vertical flap C partly balanced by weight G, an in-

clined flap F having teeth F' and F², partly controlled by weight G', said flaps being in 15 pivotal connection with the inner end of the chute by means of the pivot- rods H and H', to which the respective counterbalance-weights are rigidly secured, all substantially as specified.

Dated this 4th day of August, 1897.

JAS. TEEVAN.
JAMES F. HOYNE.
